EXERCISING TOY

Charles J. Jugans, Bloomingdale, N. J.

Application April 23, 1950, Serial No. 158,018

3 Claims. (Cl. 104—79)

1

This invention relates to exercising toys, and more particularly to an exercising toy of the seesaw type.

A main object of the invention is to provide a novel and improved exercising toy for children, said toy being very simple in construction, being safe to use, and providing useful exercise and a substantial amount of amusement to a small child.

A further object of the invention is to provide an improved exercising toy which involves relatively few parts, is very inexpensive to manufacture, is sturdy in construction, provides healthful exercise to children using the device, and is relatively compact in size.

Further objects and advantages of the invention will become apparent from the following description and claims, and from the accompanying drawings, wherein:

Figure 1 is a side elevational view of an improved children's exercising toy constructed in accordance with the present invention;

Figure 2 is a top plan view of the exercising toy illustrated in Figure 1;

Figure 3 is a cross-sectional view taken on line 3—3 of Figure 2;

Figure 4 is an enlarged cross-sectional detail view taken on line 4—4 of Figure 3;

Figure 5 is an enlarged cross-sectional detail view taken through one of the guide rollers and guide channels employed in the exercising toy of Figures 1 to 4.

Referring to the drawings, 11 designates the base of the device, said base comprising a longitudinal, flat plate member 12 having the laterally projecting side plate elements 13, 13 extending from the intermediate portion thereof. Secured to the intermediate portion of the base 11 are the inclined, longitudinally extending spring bars 14, 14 which extend toward the respective ends of the longitudinal plate member 12, as shown in Figure 1, and are formed with horizontal end portions 15 overlying the respective end portions of said longitudinal member 12.

Secured to the respective, laterally extending plate elements 13, 13 are the vertical, upstanding brackets 16, 16, which extend in the median, vertical, transverse plane of the base 11. Designated at 17 is a rectangular frame comprising inwardly facing, longitudinal side channels 18, 18 connected at their ends by transverse bars 19, 19. Secured to and depending from the outer side walls of the channel members 18 at their intermediate portions are the respective plate members 19, said plate members being formed at their

2

lower ends with inturned flanges 20, and secured to said flanges 20 are depending brackets 21 which are hinged to the top ends of the brackets 16, as shown at 22, for pivoting around a transverse, horizontal axis. Secured to the bottom walls of the channel members 18, 18 adjacent the respective ends of the frame 17 are horizontal, transverse crossbars 23, 23 to which are secured the respective, short, longitudinally extending block members 24, 24. The block members 24 overlie the respective horizontal end portions 15 of the spring arms 14, as shown in Figure 1, and each block member 24 has secured to its bottom surface a bumper element 25 adapted to engage the adjacent horizontal element 15 responsive to tilting motion of the frame 17.

Designated at 26 is a seat comprising a rectangular box-like structure having a bottom wall 27, side walls 28, 28 and a rear wall 29. Secured in the rear portion of the aforesaid box-like structure is a horizontal, transverse seat board 30, and secured to the side walls 28, 28 at their intermediate portions are vertical brackets 31, 31 to the top ends of which is secured a horizontal, transverse handle bar 32. Secured to the bottom wall 27 adjacent the forward and rear ends are transversely aligned brackets 33 in which are secured the transverse supporting rods 34, 34. Rotatably mounted on the ends of the rods 34 are the rollers 35 which are received in the respective, longitudinal channels 18, 18, as shown in Figure 3. Secured to the under side of the seat 26 is a depending bracket member 36 to which is secured a wooden block 37, as shown in Figure 4, and secured to the opposite sides of the block 37 are the respective, longitudinally directed, conical coil springs 38, 38. The springs 38, 38 are longitudinally aligned with the respective abutment blocks 24, 24 adjacent the ends of the frame 17.

In using the device, the child sits in the seat 26 and holds the handle bar 32. By movement of his body, the child tilts the frame 17, causing the seat 26 to move alternately from one end 45 of the frame to the other, the tilting movement of the frame being cushioned by the alternate engagement of the members 25 with the horizontal spring bar portions 15. At the same time, the sliding movement of the seat 26 is cushioned 50 and limited by the resilient engagement of the springs 38 with the stop blocks 24 each time the seat reaches the end of the frame. The pivoting action of the frame takes place around the horizontal, transverse axis defined by the hinges 22, 22 and the movement of the seat is limited by

the engagement of the shock absorbing springs 38 with the blocks 24, as above described, the frame being cushioned in its tilting movement by its engagement with the respective horizontal portions 15 of the spring bars 14. Consequently, the child may exercise himself actively, in order to cause the seat 26 to oscillate back and forth on the frame 17, and to cause said frame to pivot alternately in the manner of a seesaw. The device is therefore useful both for providing entertainment and amusement for children, as well as providing a means of exercising various portions of the body, the device being especially suitable for use by small children.

While a specific embodiment of a child's exercising device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A child's exercising toy for use by a single child comprising a base, a frame pivotally secured to said base for oscillation around a transverse horizontal axis spaced below the frame, a pair of longitudinal guide rails carried by said frame, a single seat slidably mounted on said guide rails, respective spring cushioning elements carried by said base extending subadjacent the ends of said frame and cushioning the oscillation of said frame produced by rocking exercising movement of a child in the seat, and cooperating stop means carried by said seat and the respective end portions of the frame arranged to limit longitudinal movement of the seat with respect to the frame caused by said rocking exercising movement.

2. A child's exercising toy for use by a single child comprising a base, upstanding bracket means at the intermediate portion of said base, a frame pivotally secured to said bracket means for oscillation around a transverse horizontal axis beneath the frame, a pair of longitudinal guide rails carried by said frame, a seat slidably mounted on said guide rails, upwardly and outwardly inclined spring arms carried by said base and extending subadjacent the ends of said frame for cushioning the oscillation of said frame produced by rocking exercising movement of a

child in the seat, and cooperating resilient stop means carried by said seat and the respective end portions of the frame arranged to limit longitudinal movement of the seat with respect to the frame caused by said rocking exercising movement.

3. A child's exercising toy for use by a single child comprising a base, upstanding bracket members on the opposite sides of the base at the intermediate portion thereof, a rectangular frame comprising a pair of inwardly facing longitudinal channel bars and respective cross bars connecting the end portions of said channel bars, depending bracket means carried by the mid-portions of the respective channel bars and hinged to said upstanding bracket members for pivotal movement around a transverse horizontal axis beneath the frame, a pair of transverse rod members, rollers journaled on the ends of said rod members and received in the respective channel bars, a seat secured on said rod members arranged to receive a single child, a depending transverse plate carried by said seat, respective longitudinal coil springs secured to the opposite sides of said plate, respective abutments secured to said cross bars engageable by said springs to limit and cushion longitudinal movement of said seat with respect to said channel bars produced by rocking exercising movement of the child in the seat, and respective upwardly and longitudinally inclined spring bars secured to the mid-portion of said base and having horizontal free ends underlying the respective cross bars, limiting and cushioning oscillations of said frame produced by the child's rocking exercising movements.

CHARLES J. JUGANS.
